UNITED STATES PATENT OFFICE.

WILLIAM H. COLDWELL, OF NEWBURGH, NEW YORK.

GEARING.

1,185,815..

Specification of Letters Patent. Patented June 6, 1916.

Application filed January 19, 1912. Serial No. 672,240.

To all whom it may concern:

Be it known that I, WILLIAM H. COLDWELL, a citizen of the United States, residing at Newburgh, in the county of Orange and State of New York, have invented certain new and useful Improvements in Gearing; and I do hereby declare the following to be a full, clear, and exact description of the invention, such as will enable others skilled in the art to which it appertains to make and use the same.

My invention consists in the novel features hereinafter described reference being had to the accompanying drawings which illustrate one embodiment of the invention selected by me for the purposes of illustration, and also a slight modification thereof and said invention is fully disclosed in the following description and claim.

Referring to the accompanying drawings, Figure 1 represents a perspective view of an embodiment of my improvement in gearing, as I have applied the same for use in driving a traction roller, the gearing being inclosed in a gear casing, the cover or closing plate of which is removed. Fig. 2 is a vertical sectional view on line 2—2 of Fig. 1 looking in the direction of the arrow. Fig. 3 is a horizontal sectional view on line 3—3 of Fig. 1. Fig. 4 is an elevation of a modification.

The object of my invention is to provide a reversible driving mechanism, which is specially well adapted for use in connection with a high speed motor or driving shaft and for starting a heavy load, provision being made for reducing the speed of the motor or driving shaft by the use preferably of worm gearing and a slip clutch mechanism being interposed between the driving and driven members to permit a slight slippage in starting and in case of extra heavy load conditions, to avoid breaking or straining the parts. I further provide improved means for reversing the direction of rotation of the driven member without altering the direction of rotation of the driving member, said reversing means being so constructed that it will bring the meshing reversing gears into exactly the proper relation with the driven gear, and further that it will be self locking, that is to say, will maintain itself in whatever position it may be adjusted to, without the use of auxiliary locking or securing means.

In the embodiment of my invention which I have selected for purposes of illustration

and which is shown in Figs. 1, 2 and 3 of the accompanying drawings, 12 represents the driving member, or shaft, which may be the driving shaft of a high speed explosive engine, or electric motor or a shaft driven in any desired manner. The driving shaft 12 has its end preferably extended into a gear casing 16, as shown, the rear wall of which is provided with one of the bearings for the shaft, but I do not limit myself to the use of a gear casing. The driving shaft 12 is preferably provided with a worm 13 secured thereto and engaging the teeth of a horizontally disposed worm wheel 14 mounted loosely on a vertically disposed connecting shaft 15 and held in position by suitable collars 14^a and 14^b secured to the shaft. The vertical shaft 15 is mounted in bearings in the walls of the gear casing, and a continuously engaged friction clutch is employed for connecting the worm wheel 14, with the shaft 15. In the present instance I have shown a cone clutch, the female member 20 of which is formed with or secured to the worm wheel 14, and a male member 21 is mounted on a spline so as to turn with the shaft 15 but to be capable of movement longitudinally thereof. A spring 22 surrounds the shaft 15 and is interposed between the male clutch member 21, and a collar 22^a adjustably secured to the shaft, thus normally holding the clutch members in frictional engagement, but permitting slippage when the load overcomes the frictional resistance of the clutch, which latter can be varied by adjusting the tension of the spring by means of the collar 22^a.

2 represents the driven shaft, here represented as the shaft of a traction roller 1, a portion of which is shown in the drawing. The shaft 2 is perpendicular to the shaft 15 and extends into the gear casing within which it is provided with a bevel gear 19. The shaft 15 is provided with two bevel pinions 17 and 18 secured to a sleeve 16, which is connected to shaft 15 by a spline so as to rotate therewith but is capable of movement longitudinally of the shaft. The pinions 17 and 18 are preferably at such a distance apart that in a median position of the sleeve neither pinion will engage the bevel gear 19, in which position the shaft 15 may be rotated without driving the shaft 2.

23 represents a shifting lever located in the gear casing and pivoted substantially centrally, said lever being provided at one end with a yoke 23^a pivotally connected to a

collar, rotatable on but secured to move end-
wise with said sleeve, the other end of said
lever being bifurcated and forming arms
indicated at 24, 24, each of said arms being
5 provided with a stop or projection 25. 26
represents an eccentric, or cam, mounted
within the gear case on a short shaft, and lo-
cated between and with its peripheral sur-
face in contact with the arms 24, 24. The
10 cam or eccentric has formed integrally with
or secured to it stop arms 27, 27, each of
which is preferably provided with an ad-
justing screw 28 adapted to engage the ad-
jacent stop or projection 25. These screws
15 are adjusted to stop the movement of the
shifting lever in each direction when one or
other of said pinions 17, 18 has been placed
accurately in mesh with the bevel gear 19,
thus insuring the gearing meshing easily
20 without undue wear or strain. As the ex-
terior surface which engages the arms 24, 24
is circular the lever 23 will be maintained in
any position to which it may be adjusted,
without the necessity of any extraneous
25 locking or securing mechanism, (that is, to
say, in the extreme positions of the eccentric
26, the points of engagement of the arms 24,
24 thereof will be in a line with a diameter
of the eccentric passing through its pivotal
30 axis, so that the arms will be unable to ex-
ert any influence on the eccentric, which
would tend to move the same, and even in in-
termediate positions of the eccentric, the
slight leverage which the arms would have
35 upon the eccentric would not be sufficient to
overcome the frictional resistance of the piv-
otal connection, and that of the actuating
mechanism connected with the eccentric.)
In other words the reversing mechanism is
40 self locking in whatever position is it placed.
The shaft of the eccentric 26 (or the ec-
centric itself) is provided with an operating
arm 29 which may be actuated by hand or in
any desired manner, and by means of this
45 arm, the sleeve 16 can be moved to hold the
pinions 17, 18 out of engagement with the
gear 19 (the median position) or to throw
either of said pinions into engagement with
the gear, and thus drive the shaft 2 in either
50 direction. The gear case is preferably fitted
with a cover 11 and is filled with lubricant
which may be in a liquid or semi-solid con-
dition, thus keeping all the parts thoroughly
lubricated.
55 In Fig. 4 I have illustrated a slight modi-
fication of my invention, in which 12^a is the
driving shaft, having the worm 13^a engag-
ing the worm wheel 14^a loose on the shaft
15^a and connected thereto by the friction
60 clutch members 20^a and 21^a and spring 22^a.
2^a is the driven shaft provided with the gear
19^a, all constructed and operating as here-
tofore described. In this instance, however,

the bevel pinions 17^a and 18^a are loosely
mounted on the shaft 15, and are held in 65
mesh with the bevel gear 19^a by suitable
collars. Each of said pinions is provided
with a clutch member 17^b and 18^b respec-
tively, and between these clutch members is
a double clutch member 16^a splined on the 70
shaft 15, and capable of longitudinal move-
ment. The shifting lever 23^a has its yoke
connected to the double clutch 16^a and said
shifting lever is provided with the arms 24^a,
stops 25^a, eccentric 26^a, carrying arms 27^a, 75
set screws 28^a and operating arm 29^a all as
hereinbefore described with reference to
Figs. 1, 2 and 3.

It is obvious that other variations may be
made in the details of the construction with-
80 out departing from my invention and I,
therefore, do not limit myself to the exact
details herein shown and described.

The mechanism for shifting the reversing
lever herein shown and described is not spe-
cifically claimed herein as the same is re-
served and will be covered by a separate ap-
plication, a division of this application.

What I claim and desire to secure by Let-
ters Patent is:—

In a driving gearing the combination with
a horizontally disposed high speed driving
shaft provided with a worm and a horizon-
tally disposed low speed driven shaft pro-
vided with a beveled gear, of a vertically
disposed intermediate shaft provided with a
worm wheel loosely mounted thereon and
engaging said worm, a friction clutch mem-
ber rigidly secured to said worm wheel, a
friction clutch member rigidly secured to 100
said intermediate shaft and engaging the
first mentioned clutch member, a spring nor-
mally holding said clutch members in op-
erative relation at a predetermined pressure,
a pair of beveled pinions mounted on said 105
vertical shaft for driving the driven shaft
in opposite directions, means for connecting
the driven shaft with the intermediate shaft
through one or other of said pinions to re-
verse the direction of movement of the 110
driven shaft and a rotary traction member
operatively connected with said driven
shaft, whereby the power of the high speed
driving shaft may be continuously imparted
115 to the intermediate shaft at reduced speed
and transmitted in either direction to the
driven shaft and rotary traction member
without danger of straining or breaking the
parts.

In testimony whereof I affix my signature, 120
in the presence of two witnesses.

WILLIAM H. COLDWELL.
